UNITED STATES PATENT OFFICE.

CARL P. SEYLER, OF PITTSBURGH, PENNSYLVANIA.

ANCHOR DEVICE.

Application filed May 21, 1927. Serial No. 193,205.

This invention relates to anchoring devices, and particularly to a combined guy rod and clamp device especially designed for securing an end of a guy or guy rope, usually comprising galvanized steel wires stranded together, used for reinforcing the poles employed in electrical transmission lines.

Guy rods, as heretofore generally employed, included a rod with an eye formed at the upper end thereof, through which the guy was looped; after the guy was pulled through the eye of the rod, the free end thereof was clamped to the guy rope by a separate clamp device positioned at a desired point above the eye.

The operation of applying the guy rope to the anchor device, as heretofore constructed, including the act of passing and drawing the rope through the eye of the rod, frequently causes the galvanizing material to be removed, thus exposing the steel guy at the point or points it is most desirable to protect, i. e., the points in the guy in contact with or adjacent to the eye of the rod. Under the old method of connecting the guy and the anchor, in which the separate means are employed, there was always considerable friction set up between the eye and the guy.

The prime object of the present invention is to provide a simple and efficient anchor device that will eliminate the objectionable features above referred to in the use of anchor devices of the character to which my invention relates.

Further objects of the present invention are, to provide a combined guy-rod and clamp means of such construction that the guy may be more conveniently attached to the anchor device than under the old construction; and a construction combining in a unit device the functions of anchoring the guy and clamping the free end of the guy to the main portion of the guy.

In the accompanying drawings, which illustrate applications of my invention:

Fig. 1 is a side elevational view of a combined guy rod and clamp device embodying my invention, showing a portion of a guy rope or guy held in position thereon;

Fig. 2, an elevational view with the clamp plate member removed;

Fig. 3, a detail elevational view of the clamp plate member;

Fig. 4, a detail end view showing the upper end of a modified form of guy rod; and

Fig. 5, a detail elevational or face view,

showing the upper portion of the modified form, the form shown in Fig. 4.

Referring to the drawings, and first to the form of Fig. 1, 5 designates the shank portion of the guy rod, which may be of any desired length and thickness. Formed integral with the shank portion, is an elongated plate-like head 6. Head 6 is designed to have a portion of a guy or guy rope 7 looped thereon and, as illustrated, is formed with a relatively large curved bearing portion 8, disposed at the point where the head joins the shank 5, to provide a continuous bearing surface for the guy. Bearing surface 8 is of sufficient area and has a radius of curvature of such a character as to permit the guy to be bent over thereon without producing injurious bending stresses in the guy when the latter is placed thereon and subjected to the tension met with in the act of drawing the guy into the desired engagement with the guy rod.

The curved bearing surface 8, on opposite sides, merges into vertically extending grooves or channels 9 formed in the head 6. These grooves 9 are adapted to receive the looped portion of the guy rope and, when the parts are assembled, the said looped portion is maintained in position in the said grooves and on the structure by means of a clamp plate member 10.

In addition to the parts or portions mentioned, the head is formed with a plurality of bolt receiving square openings 11 and with a hook or attaching means 12. The purpose of the attaching means 12 is to provide simple and efficient means for securing a tackle block or "come-along", not shown, employed in applying the guy to the head.

13 designates a series of headed and threaded bolts designed to secure the plate 10 to the head 6, and 14 designate nuts positioned on the threaded portion of the bolts. Plate member 10 is provided with bolt receiving openings 15 corresponding with the bolt receiving openings 11 of the head and through which the bolts extend when the parts are assembled. Plate member 10 is also formed with vertically extending grooves 16 similar to the grooves 9 of the head.

In the form of Fig. 4, in place of the hook member 12, I provide an eye 17 for attaching the tackle to the head 6; otherwise, the structure is the same as in the form of Fig. 1.

What I claim is:

1. In an anchoring device, the combination

with a guy-rod having an integrally formed elongated guy receiving head at one end thereof, and a curved bearing over which the guy is looped, a clamp member for clamping a looped portion of the guy on the head, and means for attaching the clamp member to the head.

2. In an anchoring device, the combination with a guy-rod having an integral elongated guy receiving head, a clamp member for clamping a looped portion of the guy on the head, and means for attaching the clamp member to the head, said head having a curved portion adapted to receive and provide a bearing surface for a guy.

3. In an anchoring device, the combination with a guy-rod having an integrally formed elongated head at one end thereof, said head having a curved portion adapted to receive and provide a bearing surface for a guy, and an upwardly extending guy receiving groove, a clamp member for clamping a looped portion of the guy on the head, and means for attaching the clamp member to the head.

4. In an anchoring device, the combination with a guy-rod having an integrally formed

elongated head at one end thereof, said head having a curved portion adapted to receive and provide a bearing surface for a guy, and over which the guy is bent and an upwardly extending guy receiving groove, a clamp member for clamping a looped portion of the guy on the head, and means for attaching the clamp member to the head, said clamp member having a guy receiving groove similar to the groove of the head, said grooves adapted to receive and provide a bearing for the looped portion of a guy.

5. In an anchoring device, the combination with a guy-rod having an integral head, said head having a curved portion adapted to receive and provide a bearing surface for a guy over which the guy is bent and a pair of upwardly extending guy receiving grooves, a clamp member cooperating with the head having a pair of upwardly extending guy receiving grooves, said grooves adapted to receive and provide bearings for the looped portion of a guy, and means for attaching the clamp member to the head.

In testimony whereof I affix my signature.

CARL P. SEYLER.
